INVENTOR:

George W. Edwards,

BY Draker & Co., ATT'YS.

UNITED STATES PATENT OFFICE.

GEORGE W. EDWARDS, OF CHATHAM, NEW JERSEY, ASSIGNOR OF ONE-HALF TO JOHN M. BALDWIN, OF SAME PLACE.

CAR-COUPING.

SPECIFICATION forming part of Letters Patent No. 380,280, dated March 27, 1888.

Application filed October 31, 1887. Serial No. 253,804. (No model.)

To all whom it may concern:

Be it known that I, GEORGE W. EDWARDS, a citizen of the United States, residing at Chatham, in the county of Morris and State of New Jersey, have invented certain new and useful Improvements in Car-Couplings; and I do hereby declare the following to be a full, clear, and exact description of the invention, such as will enable others skilled in the art to 5 which it appertains to make and use the same, reference being had to the accompanying drawings, and to letters of reference marked thereon, which form a part of this specification.

The object of this invention is to provide a 15 car-coupling which may be operated from the outside of the car, thereby avoiding the necessity and danger of raising the coupling-link with the hand by inserting it between the bumpers, as is ordinarily done.

20 The invention consists in the peculiar construction of the draw-head and in the arrangements and combinations of parts co-operating therewith, substantially as will be hereinafter set forth, and finally embodied in the clauses 25 of the claim.

Referring to the accompanying drawings, in which like letters of reference indicate corresponding parts in each of the several figures, Figure 1 is a sectional view of my improved 30 draw-head, taken through line X, Fig. 3, showing the coupling-pin and a round cross-bar or rivet, to which is secured the coupling-link. Fig. 2 is a front view of the draw-head, showing 35 a device for raising the coupling-link into engagement with the next car in the train; and Fig. 3 is a bottom view of the draw-head.

In said drawings, A indicates my improved draw-head, secured to the front of the car in the usual manner and having an open bottom, 40 as A'; b, the coupling-pin attached to a lever and operated in the usual way. Said pin is adapted to slip through an opening in a tongue, c, protruding from the bottom side of the draw-head, as in Fig. 3, said tongue being perforated 45 to receive the end of the coupling-pin b as it descends in coupling the cars.

d is a round cross-bar passing through and secured to the draw-head, on which swings a coupling-link, e, as indicated in Fig. 2. Said 50 link is actuated by a device, f—such as a lever—also shown in Fig. 2, secured to the draw-

head or car or to a cross-bar, g, of wood or other suitable material, secured to the bottom of the car, as at g', Fig. 2, said lever being of metal and fulcrumed, as at g² and g³, to said cross-bar g in said lever.

f' represents arms with which to operate the lever, and f² is another arm projecting from said lever, which actuates the coupling-link e and raises it to a position to be coupled with the adjacent car. Said lever may be operated from the outside of the car, instead of inserting the hand between the bumpers of the cars in raising the coupling-link, as before stated, thereby avoiding the danger of injury to the hands of the brakeman in coupling the cars.

The draw-head may be made in two parts, as shown, or it may be composed of an integral or solid casting.

The invention being so clearly illustrated in 70 the drawings, further description is deemed unnecessary.

Having thus described the invention, what I claim as new is—

1. A draw-head for cars, combining therein 75 a chamber in the front end, which is open at the bottom, as at A', having a tongue, c, projecting from the bottom toward the draw-head, and having an aperture therethrough to admit of the passage of the pin, and having a cross-bar, as d, to serve as a journal for a coupling-link, substantially as and for the purposes set forth.

2. The combination, with a draw-head provided with a chamber at the front end, having 85 an open bottom and a perforated tongue, as described, of a cross-bar, as d, a coupling-link journaled upon said cross-bar, and a lever fulcrumed beneath the bottom of the car, having an arm extended to the outside of said car, and 90 adapted to raise said coupling-link in a position to engage with the draw-head of the adjacent car, substantially as and for the purposes set forth.

In testimony that I claim the foregoing I 95 have hereunto set my hand this 6th day of October, 1887.

GEORGE W. EDWARDS.

Witnesses:

OLIVER DRAKE,
OSCAR A. MICHEL.
